(57) **CLAIM**

The ornamental design for a loudspeaker, as shown and described.

DESCRIPTION

FIG. 1 is a left perspective view of the loudspeaker showing the new design;

FIG. 2 is a right perspective view thereof;

FIG. 3 is a rear perspective view thereof;

FIG. 4 is a front elevation view thereof;

FIG. 5 is a right elevation view thereof;

FIG. 6 is a left elevation view thereof;

FIG. 7 is a top plan view thereof; and,

FIG. 8 is a bottom plan view thereof.

(Continued)

The broken lines shown in the drawings represent unclaimed portions of the loudspeaker and form no part of the claimed design.

1 Claim, 8 Drawing Sheets
